UNITED STATES PATENT OFFICE.

WILLIAM S. GUBELMANN, OF BUFFALO, NEW YORK.

PAPER-SUPPORTING MECHANISM FOR RECORDING-MACHINES.

1,372,748.

Specification of Letters Patent. Patented Mar. 29, 1921.

Original application filed January 10, 1900, Serial No. 1,004. Divided and this application filed July 5, 1918. Serial No. 243,444.

To all whom it may concern:

Be it known that I, WILLIAM S. GUBELMANN, a citizen of the United States, residing in Buffalo, in the county of Erie and State of New York, have invented certain new and useful Improvements in Paper-Supporting Mechanism for Recording-Machines, of which the following is a specification.

10 The present invention relates to mechanism for supporting paper rolls from which the paper is fed to be printed upon, and is adapted for use in calculating machines, cash registers, type writers, and other machines of this type. The present application is a division of my pending application Serial No. 1,004.

Only such of the mechanism herein described as refers to paper supporting mechanism for recording machines is claimed herein.

In the original application 1,004, filed Jan. 10, 1900 is claimed grand total mechanism and combinations therewith.

25 The following is a list of the divisions of said parent application 1,004, and the subjects matter claimed in each.

Serial No. 183,397, filed July 30, 1917, general combinations of all the mechanism 30 of the machine, exclusive of the grand total mechanism and not falling more particularly under one of the other division.

Serial No. 183,398, filed July 30, 1917, general combinations drawn to a simple 35 adding machine.

Serial No. 254,065, filed Sept. 14, 1918, ribbon feeding and reversing mechanism.

Serial No. 123,842, filed Oct. 5, 1916, printing mechanism.

40 Serial No. 130,583, filed Nov. 10, 1916, key mechanism.

Serial No. 251,476, filed Aug. 26, 1918, counting mechanism.

45 Serial No. 257,465, filed Oct. 9, 1918, numbering mechanism.

Serial No. 264,629, filed Nov. 27, 1918, mechanism for transforming an adding and listing machine into a counting and numbering machine.

50 Serial No. 244,575, filed July 12, 1918, horizontal ruling mechanism. Patented Mar. 9, 1920, No. 1,333,307.

Serial No. 245,336, filed July 17, 1918, vertical ruling mechanism.

Serial No. 258,051, filed Oct. 14, 1918, 55 split calculating machine.

Serial No. 242,395, filed June 28, 1918, carriage mechanism.

Serial No. 246,158, filed July 22, 1918, 60 non-print mechanism.

Serial No. 248,127, filed Aug. 3, 1918, eliminating mechanism.

Serial No. 249,303, filed Aug. 10, 1918, repeating mechanism.

Serial No. 260,030, filed Oct. 28, 1918, carriage mechanism.

Serial No. 261,806, filed Nov. 9, 1918, distinguishing means for the keys and dials.

Serial No. 249,905, filed Aug. 14, 1918, key interlocking mechanism. Patented 70 Mar. 23, 1920, No. 1,334,533.

Serial No. 250,536, filed Aug. 19, 1918, duplicate printing mechanism.

Serial No. 251,778, filed Aug. 28, 1918, 75 word printing mechanism.

Serial No. 256,263, filed Sept. 30, 1918, dating mechanism.

One of the objects of the invention is to provide means whereby a paper roll may be supported in proper relation to a platen. 80

Another object is to provide means whereby a plurality of paper rolls may be supported in proper relation to a platen.

Another object is to provide means for supporting the paper rolls on a horizontally 85 movable carriage so that they move with the carriage in its horizontal movements.

Another object is to provide adjustable paper roll supports whereby rolls of different widths may be accommodated by the same 90 supports.

Other objects will appear from a reading of the following description and claims the means for attaining all of these objects being illustrated in the accompanying drawings consisting of three sheets in which:

Figure 1 is a vertical longitudinal sectional view of a machine embodying my invention and showing the mechanism in the normal or inactive position. 100

Fig. 2 is a fragmentary transverse section, taken in line 2—2, Fig. 1 and showing the means for adjusting the paper carriage lengthwise of the line printing.

Fig. 3 is a vertical section, taken substantially in line 3—3, Fig. 1.

Fig. 4 is a fragmentary longitudinal sectional elevation showing particularly the

paper carriage and the mechanism whereby different parts of the machine may be thrown into and out of gear.

Fig. 5 is a vertical transverse section, on a reduced scale, taken in line 5—5, Fig. 4, and showing the means for supporting two rolls of web-paper, for manifold recording.

Fig. 6 is a detached side elevation of the paper carriage, viewed from the side opposite to that shown in Fig. 4.

Fig. 7 is a fragmentary vertical section, taken in line 6—6, Fig. 5, and showing the means for holding the paper spindle in place.

Like letters of reference refer to like parts in the several figures.

While the invention as disclosed in the parent application is embodied in a machine for adding numbers, the principles and construction may be usefully employed in machines for various other purposes. Therefore, in the accompanying drawings and description, the adding mechanism is omitted.

General construction.

1 represents the main frame of the machine which may be of any suitable construction so as to support the working parts of the machine.

5 represents the main gear segments, which in the parent application are utilized to operate suitable accumulating mechanism and which in the present instance are used to move type carriers to position their various types. Each of these gear segments is arranged in rear of its companion gear pinion and is provided at its lower end with a rearwardly projecting arm 6 which is pivoted loosely on a transverse supporting rod 7. This rod is mounted with its ends on the upper ends of two rock arms 8 which turn loosely with their lower ends on a transverse rock-shaft 9. The rock-arms 8 are connected by a transverse bar 10 which compels the two arms to move back and forth together, but for the purpose of the present application, it may be considered that the arms 8 are stationary, and the back-and-forth movement may be disregarded.

15 represents a rocking frame which is secured with its lower portion to a transverse rock-shaft 20 journaled in the main frame and provided outside of the frame with a hand crank, whereby this shaft is rocked and the parts connected therewith are operated.

The gear segments 5 are raised to their highest position by means of a return or lifting bar 22 which extends transversely underneath all of the arms 6 of the gear segments and which is connected loosely at its rear ends with the transverse rod 7 by lifting plates 23. 24 represents two shifting arms which are mounted loosely at their rear ends on the rock-shaft 20 and which support

at their other ends a transverse bar 25 which transverse bar is connected at its ends by two links 26, with the lifting plates 23, whereby upon raising the shifting arms 24, the lifting bar 22 is caused to raise the gear segments and the other parts connected therewith resting on said bar. Upon depressing the transverse bar 25, the lifting bar 22 is moved downwardly and the gear segments resting thereon are permitted to move downwardly with the bar until the segments are arrested.

Each of the gear segments is yieldingly held in contact with the lifting bar 22 by a spring 27 which connects the arm of the segment with the transverse bar 25. If the downward movement of the gear segment is arrested while the shifting arms 24 continue to move downwardly, the lifting bar 22 is moved away from the underside of the arm of the gear segment and the spring 27 is strained. The transverse bar 25 is arranged at one end in a segmental notch 28 formed in the front part of the rocking frame 15, shown in Fig. 1 and its opposite end is arranged in a similar segmental notch 23 formed in a rocking frame 29 which is secured to the operating shaft 20 on the left-hand side of the machine. The rocking frames 15 and 29 together with the operating shaft 20 constitute the main or universal operating frame of the machine. When the machine is at rest, as shown in Fig. 1 the transverse bar 25 engages with the front side of the notches 28 in the rocking frames 15 and 29. Upon turning the rocking shaft 20 forwardly, by means of its handle 21, in the direction of the arrow, Fig. 1, the rocking frames are moved forwardly during the first part of the movement independent of the transverse bar 25, the extent of their notches 28 along the ends of the bar 25 without disturbing the latter. The continued forward movement of the rocking frames causes the rear ends of their notches 28 to engage with the bar 25 and depress the same thereby causing the lifting bar 22 to be moved downwardly and strain the springs 27. This causes all of the gear segments which are free, to be moved downwardly and to continue their downward movement until they are arrested. The extent which each segment moves depends upon the position in which it is arrested. After the segments have been arrested in their downward movement, they remain in this position while the rocking frames complete their forward movement.

Upon now turning the rock-shaft 20 backwardly by means of the handle 21, the rocking frames are moved backwardly, until the front ends of the notches engage with bar 25. When the latter is so engaged it is moved backwardly with the rocking frames to the end of their rearward movement.

which causes the transverse bar 25 to lift the lifting bar 22 and the gear segments which have been depressed into their highest or normal position.

5 30 represents a number of elbow-shaped controlling arms, which form part of the devices whereby the downward movement of the registering gear segments is controlled. One of these arms is arranged along the left-hand side of each gear segment and consists of an upright front part and a horizontal lower part which extends rearwardly from the lower end of the upright part, thereby leaving a clear space in rear of the upright 10 part of the controlling lever, as represented in Fig. 1. The rear end of the lower part of each controlling arm is mounted loosely on a transverse supporting bar 31, while the upper end of its front or upright part is loosely connected with the upper portion of 15 its companion gear segment. This loose connection permits the controlling arm and the gear segment to swing freely about their individual axes, which are arranged parallel but out of line. While a movable connecting member is provided between the controlling arm and its companion gear segment, for the purpose of the present application, the segment and controlling arm are 20 25 to be considered as immediately contacting.

In the uppermost position of the controlling arms the same bear with their upper ends against a transverse stop bar 32, as shown in Fig. 1, which limits the upward 30 movement of these arms. Each controlling arm is provided on the rear part of its upper end with a locking lug 33, and on the front part of its upper end with a stop lug 34, both of which lugs project toward the left 35 and are preferably stamped out in one piece with the controlling arm.

The operation of the registering devices is controlled by a number of elbow-shaped key levers which are arranged side by side 40 and pivoted to a transverse supporting rod 35. Each key lever is provided with a lower actuating arm 36, which projects forwardly, and an upper stop arm 37 which projects upwardly along the left hand side 45 of one of the controlling arms and gear segments as represented in Fig. 1. Each of these key levers is provided on the rear side of its stop arm with a locking shoulder 38 which is adapted to engage with the locking lug 33 of the controlling arm when the latter 50 is elevated into its highest position and the key-lever is in its fully retracted position, as shown in Fig. 1. When the parts are in 55 this position, the key lever holds the controlling arm against downward movement and the latter holds the gear segment against downward movement. While the gear segment is so held against downward movement, if the rocking frames are turned forward 60 for depressing the gear segment, the

spring 27 of this segment will be strained without, however, shifting the segment.

The upper arm of each key lever is provided on its front side with a vertical series of differential stop shoulders 39, which are 70 arranged step fashion and extend from the upper end of this arm downwardly and forwardly thereon or in other words the stop shoulders 39 are arranged radially out of line with one another and different distances 75 from the pivot of the key lever. These stop shoulders of the key lever are adapted to be moved forwardly into the path of the stop lug 34 on the controlling arm. The stop shoulders are arranged different distances 80 from the stop lug 34 of the controlling arm, so that by moving different stop shoulders of the key lever into the path of the stop lug of the controller arm, the latter and the gear segment connected therewith may be 85 arrested at different points in their downward movement. The uppermost stop shoulder of the key lever is most remote from the stop lug of the controlling arm and therefore requires the greatest forward 90 movement of the key lever, in order to bring this stop shoulder into the path of this stop lug.

The stop shoulders of the key lever are so arranged that the distance from the stop 95 shoulders to the path of the stop lug gradually grows less from the uppermost stop shoulder to the lowermost stop shoulder. When the key lever has been moved forwardly, so as to disengage its locking shoulder from the locking lug and moves one of its stop shoulders into the path of the stop lug of the controlling arm, the latter arm and gear segment connected therewith will be moved downwardly upon moving the 100 rocking frames forwardly, until the stop lug of the controlling arm strikes the respective stop shoulder of the key lever which stands in its path. By turning the key lever forward more or less and moving one or the 105 other of its stop shoulders into the path of the stop lug 34 of the controlling arm, the distance which this arm descends can be varied, thereby varying the number of 110 spaces which its gear segment turns. 115

Key mechanism.

40 represents the keys whereby the key levers are operated, and which are guided with their depending stems in the top 41 120 and bottom 42 of the keyboard. A separate row of keys 40 is provided for each of the key levers 36-37 in the machine.

Each of the registering keys is yieldingly held in an elevated position by a spring 43 125 surrounding the stem of the key and connected at its upper end to the key and bearing with its lower end against the bottom of the key-board. The upward movement of each key is limited by a shoulder 44 formed 130

on the upper part of its stem and engaging with the underside of the top of the key-board.

The downward movement of all of the 5 keys is substantially the same, but the arrangement of each column of keys lengthwise of the lower actuating arm of each key lever causes the keys to bear against their lever at different distances from its pivot, so 10 that by depressing different keys the same distance, the key lever will be turned different distances. The keys which bear against their respective key levers nearest the pivot, throw the key levers the greatest distance 15 and shift the uppermost shoulders into the path of the stop lug 34 of the respective controlling arms. The throw of each key lever upon depressing any one of its keys is so 20 adjusted, that the proper stop shoulder on its upper arm is moved into the path of the stop lug 34 of the controlling arm and the downward movement of the respective gear segment is arrested after having turned a 25 number of spaces corresponding to the key which is depressed.

Recording mechanism.

140 represents a printing roller or platen which is arranged transversely in the upper, 30 rear part of the machine and under the lower side of which the sheet or other article is placed which receives the record. 141 represents a number of type segments which are arranged transversely side by side below the 35 platen and which are pivoted at their front ends to the supporting bar 31 upon which the rear ends of the controlling arms 30 are pivoted. Each of these type segments is provided at its rear end with a segmental 40 row of type carriers 142, which are capable of moving radially back and forth on the type segment.

Each of the type carriers is provided at its 45 rear end with a type and is guided upon the type segment by means of screws or rivets 143 secured to the type carrier and arranged in radial slots 144 formed in the type segment, as shown in Fig. 1. Each of the type carriers is held in its inward or retracted position by means of an S-shaped 50 spring 145, which is arranged between the carrier and the type segment and is secured with one end to the carrier and with its other end to the type segment. Upon raising or 55 lowering the type segment any one of its type can be brought to the printing point or line, and upon striking the back or inner end of the type carrier, when the same is in line with the printing point the type carrier 60 will be driven outwardly and its type will produce an impression on the sheet supported by the platen. After the carrier has received the blow for driving the same against the platen, the carrier is again

quickly retracted to its innermost position 65 by means of its spring.

Each of the type segments is connected with one of the controlling arms, so that upon depressing a controlling arm and the registering gear segment connected therewith, the companion type segment will move 70 the proper type to the printing point.

For convenience in operating the machine, the keys are separated a considerable distance on the key-board and in order to produce a compact record, the printing segments are arranged closer together than the 75 keys and the registering mechanism. In order to permit of this arrangement, each type segment and its corresponding controlling arm are connected by a connecting arm 146, as represented in Fig. 1. The connecting arms of the central controlling arms and type segments are comparatively 80 straight, but the connecting arms of the 85 outer type segments and controlling arms are arranged obliquely, the degree of this obliquity gradually increasing from the central type segments and controlling arms in 90 opposite directions toward the outer type segments and controlling arms. The connecting arms 146 of the outer controlling arms are arranged in the spaces behind the upright parts and above the horizontal parts 95 of the controlling arms, thereby permitting the inner controlling arms to move up and down without interfering with the connecting arms 146 of the outer controlling arms.

The types on each type segment are 100 arranged to correspond with the teeth of its companion gear segment. When the registering gear segment is in its highest position the type segment presents its highest type to the printing position, and as the gear segment moves downwardly the type segment is 105 correspondingly moved upwardly so as to successively present its types to the printing position.

147 represents a number of type driving 110 hammers whereby the types at the printing position are driven to print. Any suitable controlling mechanism for the hammers whereby operation of the operating lever and shaft 20 effect printing of the desired 115 types under control of the keys, may be provided. In the drawings I have shown the mechanism for this purpose to be that described in full in the parent application Serial No. 1,004, but as this is not an essential feature of the invention sought to be covered in the present application, I shall 120 not fully describe this mechanism here.

Platen mechanism.

The mechanism whereby the platen is 125 supported and operated and the sheet or other impression surface which receives the

record as presented to the printing line, is constructed as follows:—

The frame of the carriage which supports the platen, paper and inking device consists of a transverse supporting sleeve 260 arranged in rear of the printing mechanism and provided at opposite ends with two upwardly and forwardly projecting arms 261 and with two upwardly and rearwardly projecting arms 262, as represented in Figs. 1, 2, 3, 4, 5 and 6. The supporting sleeve is arranged to slide transversely on a rod or track 263 which is secured with its ends to the sides of the frame.

15 The platen is journaled in the upper ends of the front arms 261 of the paper carriage and is held in position at the printing line by means of a catch 264 which engages with its front hooked end over a transverse rod 265 arranged below the platen and secured with its ends to the sides of the main frame, as represented in Figs. 1 and 6. This catch is yieldingly connected with the paper carriage, so as to permit the platen to recede 25 more or less from the printing mechanism for the purpose of adjusting the platen to the thickness of the sheet of paper or other object which receives the impression and which is interposed between the platen and 30 the printing types. This yielding connection forms no part of the invention claimed in the present application and will therefore not be described in full. For the purpose of the present application any suitable means 35 may be employed for the purpose of holding the platen in printing relation with the printing types.

When printing upon a sheet of paper, this sheet is fed forwardly underneath the 40 platen and upwardly in front of the same so that the sheet passes the printing line. The sheet is pressed against the under side of the platen, in rear of the printing line, by a transverse presser roller 270 arranged 45 below the platen and journaled with its ends in the front arms 261 of the paper carriage.

When it is desired to print upon a roll or web of paper, this roll is supported in 50 rear of the platen and fed with its web around the platen in the same manner in which a sheet is fed. As shown in Figs. 1, 4 and 6, an upper roll of paper is supported upon a divided spool consisting of two sections 271 which support opposite ends of the roll. 272 represents a horizontal supporting spindle which extends through the center of the upper roll of paper and through the sections of its supporting spool 55 and which is supported at its ends in openings formed in the rear arms 262 of the paper carriage. This spindle is held against displacement in the paper carriage by a catch 273 pivoted to one of said arms 60 262 and engaging with a notch or groove 274

formed in said spindle, as represented in Figs. 5 and 7.

The paper roll may be held against longitudinal displacement on the spindle by any suitable means, for instance by engaging one 70 of its spool sections against one of the rear carriage arms and a clamping collar 275 secured to the spindle and bearing against the outer side of the other spool section as represented in Fig. 5. By moving the sections 75 of the roll-supporting spool toward and from each other on the spindle the spool can be adjusted to suit different widths of paper.

When it is desired to print the record in 80 duplicate, a duplicate roll or web of paper is fed simultaneously with the main sheet or web past the printing line. The duplicate roll or web of paper is preferably supported below the main roll on the sections 85 276 of a divided spool which is mounted on a spindle 277. This roll spindle is supported at its ends by means of hangers or hooks 278 which engage with the ends of the rear arms of the carriage, as shown in Figs. 90 4, 5 and 6. The lower spool is held on the spindle by a collar 279 and the lower spindle is held in place on the hangers by a catch 280.

Platen feed or line-spacing.

95

283 represents a platen feed lever which is pivoted loosely on the left end of the platen shaft and which is provided on its rearwardly projecting arm with a pawl 284 100 which engages with a ratchet wheel 285 secured to the adjacent end of the platen, as represented in Fig. 4.

The rocking motion of the intermediate lever is always the same, and in order to 105 enable the same to turn the platen different distances, the rear arm of the intermediate lever is provided on its under side with a number of notches 292 which are arranged different distances from its fulcrum, and one or another of which is engaged by the lower end of the loop 288 on the connecting link 287. Upon engaging this loop with the notch of the intermediate lever nearest its axis, the ratchet pawl is shifted so that the platen is turned one line-space at a time; while upon shifting this loop into engagement with one of the outer notches of the intermediate lever, the platen will be turned forward by its ratchet mechanism a correspondingly greater distance by the operation of the machine.

The intermediate lever is turned in the direction for shifting the platen, by a transverse bar 293 arranged below the front arm 125 thereof, as represented in Figs. 1 and 4. This bar is supported upon the upper ends of two rock arms 294 which are mounted loosely with their lower ends on the cross bar 167. 295 represents a depending arm 130

which is preferably formed in one piece with that one of the arms 294 arranged on the left hand side of the machine. This depending arm is provided with a nose 5 which is arranged in rear of and in the path of the rocking frame 29.

During the last portion of the rearward movement of this rocking frame, it engages with the nose of the depending arm 295 and 10 moves the same rearwardly, and the upper arms 294 connected therewith are moved forwardly, thereby causing the cross bar 293 to be carried upwardly and turn the intermediate lever in the direction for feeding 15 the platen and paper forwardly. During the forward movement of the rocking frame 29, the rock arms 294 are turned backwardly together with the intermediate lever and connecting parts by the spring 289 prepara- 20 tory to feeding the platen forward the next space. As the line-spacing of the record sheet by feeding the platen occurs after each item is printed and in the same operation in which said item is printed, the 25 printed record is fed up into visible position at each operation of the machine.

If desired the platen may be turned by hand when it is desired to adjust the paper, this being effected by releasing the pawl 284 30 from the ratchet wheel and then turning the platen by means of a button 296 secured to one end of the shaft, as shown in Fig. 3.

The cross bar 293 extends a sufficient distance transversely of the machine so as to 35 engage with the front arm of the intermediate rock lever 286 in all the positions which the paper carriage can be shifted transversely, in the machine.

40 *Horizontally movable carriage.*

The paper carriage is capable of sliding lengthwise on the rods 263 and 265 for presenting different parts of the paper to any particular type and is held in its adjusted 45 position, by a spacing device which consists of a graduated adjusting sleeve 301 and an adjusting catch 302, as represented in Figs. 1 and 2. The adjusting sleeve is revolvably mounted on the supporting sleeve 260 between the carriage frame arms 261 and is provided with two or more longitudinal series of step notches or graduations 303, 304. The notches in each series may be equidistant and the notches in one series are spaced 50 different from the notches in the other series, as shown in Fig. 2. The catch 302 is pivoted on the rod 167 and is yieldingly held in engagement with any one of the notches in the adjusting sleeve 301 by a spring 305. 55 When it is desired to shift the carriage intermittently short distances lengthwise of the platen for writing narrow columns, the adjusting sleeve is turned so as to present its closely spaced notches to the catch and 60 the latter is shifted from one of these 65 notches to another as the writing progresses.

When wider columns are to be written the adjusting sleeve is turned so as to present correspondingly wider spaced notches to the catch. As shown in the drawings, only 70 two series of adjusting notches are provided on the adjusting sleeve, but more series of notches may be provided if necessary.

If desired sheet paper may be substituted for web paper, to receive the record without 75 changing the parts of the machine, but the devices for holding the rolls of web paper may be removed from the machine when writing upon sheet paper.

While I have shown inking ribbons 306 80 and 307, any suitable inking means may be employed; and if ribbons are used, any suitable means may be employed for feeding the same.

While I have described the invention as 85 applied to a key-set machine, it could be employed equally well in a key-operated machine.

I claim:

1. The combination of a movable carriage, a platen supported thereby, paper-supply-roll-supporting means supported by said carriage and adapted to be moved therewith and to hold a roll of paper, and separately operable printing types correlated 90 with said platen for printing, a plurality of which types can be impressed on said paper during a time when said paper is unmoved in the direction of any of its edges.

2. The combination of a movable carriage, a platen supported by and movable with said carriage, paper-supply-roll-supporting means supported by said carriage and arranged to move with the carriage and to receive a ready-wound roll of paper, 100 and printing types correlated with said platen for printing on said paper.

3. The combination of a movable carriage, a platen supported by and movable with said carriage, paper-supply-roll-sup- 105 porting means supported by said carriage and arranged to move with the carriage and to receive a ready-wound roll of paper, and separately operable printing types corre- 110 lated with said platen for printing on said paper, a plurality of which said types is operable to coöperate with said platen so as to effect impressing of a plurality of said types on said paper during a time in which the paper is unmoved in the direction 115 of any of its edges.

4. The combination of a movable paper-carriage; a pair of paper roll supports for holding a roll of paper in operative rotation to said paper carriage and adapted to engage 125 with the opposite ends of a roll of paper so as to support said roll and allow paper to be unwound therefrom, one of said supports being adjustable relative to the other, means for maintaining the relative adjust- 130

ment of said supports, and separately operable types, any predetermined plurality of which may be arranged to be impressed during a time when said roll of paper is unmoved in the direction of any of its edges.

5. The combination of a plurality of types; a paper-carriage movable transversely of said types; a pair of paper-roll-supports mounted on and movable with said carriage for holding a roll of paper in operative relation to said paper-carriage and adapted to engage with the opposite ends of a roll paper so as to support said roll and allow paper to be unwound therefrom, 10 one of said supports being adjustable relative to the other; means for maintaining the relative adjustment of said supports; and means for effecting impression of any one of said types on paper unwound from 15 said roll in any one of a plurality of the transverse positions of said paper-carriage.

6. In a printing machine, the combination of a plurality of separately operable types, a carriage movable with relation to said types, means supported on and movable with said carriage and adapted to carry a plurality of paper rolls in operative relation to said types; and means coöperative with said types for effecting impression on a plurality of said paper-rolls by a plurality of said types during a single operation of the last said means.

7. In a printing machine the combination of a plurality of separately operable printing types, manipulative members for controlling said types, paper roll supporting means for supporting a plurality of rolls of paper, a platen for supporting paper unwound from a plurality of said rolls in position to receive printing by said type, and means for shifting said platen and said paper roll supporting means transversely of said type in a direction parallel to the line of printing.

45 8. The combination of a plurality of printing types; a carriage movable transversely with relation to said types; a plurality of paper-roll supports each supported by and movable with said carriage; a plurality of paper-rolls supported by said paper-roll supports, a plurality of inking devices, one device for each of a plurality of said paper-rolls, each device being coöperative with said types for effecting printing 50 on paper unwound from its respective paper-roll; and manipulative members operable for controlling printing by said types on portions of paper unwound from said paper-rolls.

60 9. In a machine for printing along horizontal lines, the combination of a platen movable along a path parallel with said horizontal lines, paper-supply-roll-supporting means normally movable horizontally parallel with the movement of said platen and

adapted to hold a roll of paper, and separately operable printing types correlated with said platen for printing and a plurality of which types can be impressed on said paper during a time when said paper is unmoved in the direction of said horizontal lines.

10. In a machine for printing along lines, the combination of a platen movable along a path parallel with said lines, paper-supply-roll supporting means normally movable parallel with the movement of said platen along its side path and adapted to receive a ready-wound roll of paper, and printing types correlated with said platen 75 for printing on said paper.

11. In a machine operable to print along horizontal lines; the combination of a paper-carrying device movable along a path parallel with said horizontal lines, a pair of spool sections normally movable horizontally by movement of said paper carrying device and rotatable relative thereto and adapted to engage with the opposite ends of a roll of paper so as to support said roll 85 and allow paper to be unwound therefrom, one of said spool sections being adjustable relative to the other, means for maintaining the relative adjustment of said spool sections, and types operable to print along said 90 horizontal lines on paper unwound from said roll.

12. The combination of a plurality of sets of numeral types each set of which comprises types one to nine inclusive and operable to print in horizontal lines; paper-roll-supporting means; a platen correlated with said types; a carriage supporting the platen and paper-roll-supporting means and movable therewith relatively to said sets 100 of types, in a path parallel with the said horizontal lines; a plurality of series of type-selecting keys comprising a respective series for each set of a plurality of said sets of types, a plurality of keys of each of said series comprising a respective key for each one of a plurality of types of its respective set; and a manipulative operation-controlling member operable to effect impressing 105 at an operation thereof the type or types 110 selected by said selecting elements, on said paper, and for effecting the feeding of said paper from said roll to different print-receiving positions of said paper.

13. In a printing mechanism, the combination of a paper-roll-support constructed and arranged for the purpose of receiving a ready-wound roll of paper and for permitting paper to be unwound therefrom; paper-backing means in position for backing 120 a portion of the paper unwound from said roll of paper; a supporting frame common to said paper-roll-support and said paper backing means, for supporting them; types movable toward said paper backing means, 125 130

- for coöperating therewith so as to effect printing on the unwound portion of said paper; keys for controlling the printing by said types; a supporting frame common to 5 said types and said keys, for supporting them; and means for securing the first said supporting frame and the second said supporting frame together in rectilinearly movable relation to one another.
- 10 14. The combination of a plurality of printing types, a platen for backing a record sheet to be printed on by said types, a carriage supporting said platen and adapted to move the same horizontally crosswise of 15 said types for bringing different horizontal portions of said record sheet into coöperative relation to said printing types, and a paper-roll supporting means adapted to move with said carriage crosswise of said 20 types and to receive and support a ready wound roll of paper in such positions as to permit paper to be unwound therefrom and fed to said platen for receiving printing from said types in any one of said different horizontal positions of said paper.
- 15 15. The combination of a plurality of printing types a platen for backing a record sheet to be printed on by said types, a carriage supporting said platen and adapted 30 to move the same horizontally crosswise of said types for bringing different horizontal portions of said record sheet into coöperative relation to said printing types, and a paper roll supporting means mounted on 35 and movable with said carriage and adapted to receive and support a ready wound roll of paper in such position as to permit paper to be unwound therefrom and fed to said platen for receiving printing from said 40 types.
16. The combination of a plurality of printing types, of a platen for backing a record sheet to be printed on by said types, a carriage supporting said platen and adapted to move said platen horizontally 45 crosswise of said types, paper roll supporting means supported by said carriage and movable therewith and adapted to support a roll of paper so as to permit paper unwound therefrom and fed to said platen to be printed on by said types. 50
17. The combination of a plurality of printing types, of a platen for backing a record sheet to be printed on by said types, an operating member for effecting printing 55 of a plurality of said types on said record sheet at a time during which said platen is unwound crosswise of said types, a carriage supporting said platen and adapted to move the same transversely of said types for bringing different horizontal portions of 60 said record sheet into coöperative relation to said printing types, and a paper roll supporting means adapted to support a roll of paper and permit its movement transversely of said types under control of said carriage 65 to such position as to permit paper to be unwound therefrom and fed to said platen for receiving printing from said types in a plurality of horizontal print receiving positions. 70
